UNITED STATES PATENT OFFICE.

HARRY T. LOOMIS AND DOROTHY Z. HUNT, OF BROOKLYN, NEW YORK.

PUTTEE.

1,300,851.

Specification of Letters Patent.

Patented Apr. 15, 1919.

Application filed May 6, 1918. Serial No. 232,699.

To all whom it may concern:

Be it known that we, HARRY T. LOOMIS and DOROTHY Z. HUNT, citizens of the United States, and residing at Brooklyn, in the county of Kings and State of New York, have invented certain new and useful Improvements in Puttees, of which the following is a specification, such as will enable those skilled in the art to which it appertains

10 to make and use the same.

This invention relates to puttees, and the object thereof is to provide an improved device of this class comprising a flexible strip of predetermined length and adapted to be wrapped around the lower part of the leg in the usual manner and to be secured in place so that the separate coils thereof will not slip down but will be held in proper position at all times.

15 The invention is fully disclosed in the following specification, of which the accompanying drawing forms a part, in which the separate parts of our improvement are designated by suitable reference characters 20 in each of the views, and in which:—

Figure 1 is a side view showing our improved puttee in use;

Fig. 2 a front view thereof;

Fig. 3 a view of the device detached;

30 Fig. 4 a section on the line 4—4 of Fig. 2; and,

Fig. 5 a view indicating the manner of folding the puttee up.

In the practice of our invention, we provide 35 a flexible strip *a* of fibrous or other suitable material of predetermined length and width and one end of which is reinforced as shown at *a*² and a flexible and elastic metal strip *b* is rotatably connected with the reinforced 40 end *a*² of the strip *a*, as shown at *b*², and the strip *b* is provided on its outer surface with projecting, pointed, and preferably upwardly directed teeth members *b*⁴ which are also preferably stamped from the body of 45 said strip.

The other end portion of the strip *a* is provided with a buckle *c* and a strap keeper *d*, and a strap *e* is connected to the buckle *c* and adapted to be passed around the leg 50 and secured as shown in Fig. 1.

When the device is not in use the strip *b* is turned longitudinally of the puttee strip *a*, as indicated in dotted lines in Fig. 3 and as shown in full lines in Fig. 5, and the device may be rolled up as shown at *f* in Fig. 5 for packaging, shipment or similar pur-

poses, but when it is desired to place the device in use, it is unrolled and the strip *b* turned into the position shown in full lines in Figs. 2 and 3 and the device is applied 60 to the leg, as indicated in Figs. 2 and 1, in which operation the end *a*² thereof is placed at or around the top of the shoe *g* with the strip *b* extending upwardly at the front of the leg, and the strip *a* is passed around the 65 leg in a series of spiral coils *h*, as clearly shown, in which operation the teeth *b*⁴ of the strip *b* engage the material of said coils and hold them in proper position at all times and prevent them from slipping downward, 70 and when the strip *a* is fully wound as indicated in Fig. 1, the top coil *h* is secured by the strap *e*.

The teeth *b*⁴ on the strip *b* may be formed in any desired manner and may be made of 75 any desired length, all that is necessary being that said teeth project into the successive coils *h* as they are wound around the lug and said teeth should not be long enough to project through said coils or the overlapping 80 parts thereof; and while we have shown and described the strip *b* as connected with one end of the part *a* or body portion of the puttee, our invention is not necessarily limited to this construction as said strip *b* might 85 be used without being connected to the part *a* and other changes in and modifications of the construction herein described may be made, within the scope of the appended 90 claims, without departing from the spirit of our invention or sacrificing its advantages.

Having fully described our invention what we claim as new and desire to secure by Letters Patent, is:—

1. A puttee comprising a strip of flexible 95 material provided at one end with a pivoted flexible strip having projecting teeth.

2. A puttee comprising a strip of flexible material reinforced at one end and provided with a pivoted strip having projecting teeth 100 and adapted to be folded longitudinally thereof or transversely thereof.

3. A puttee comprising a flexible strip of predetermined length and width and provided at one end with a rotatable strip mounted centrally thereof and provided with projecting teeth, said flexible strip being also provided at the other opposite end with a securing strap and buckle. 105

4. A puttee comprising a strip of flexible 110 fibrous material and of predetermined length and width, said strip being reinforced at one

end and provided with a metallic strip which is pivoted thereto and adapted to be turned longitudinally of the fibrous strip and at right angles thereto.

5. The combination with a puttee, consisting of a strip of flexible fibrous material of predetermined width and length and adapted to be wound around the leg in the form of a spiral, of a narrow flexible supporting 10 strip adapted to be arranged longitudinally of the fibrous strip and at right angles thereto and longitudinally of the leg and provided on one face thereof with a plurality of pointed projecting devices adapted to engage the inner face of said fibrous strip when the latter is wound around the leg and over said flexible strip.

6. The combination with a puttee strip of fibrous material and of predetermined length 20 and width and adapted to be wound around

the leg in the form of a spiral, of a thin flexible strip adapted to be placed longitudinally of the fibrous strip when the latter is not in use and to be arranged longitudinally 25 of the leg when the fibrous strip is being wound around said leg, said thin flexible strip being provided with outwardly and upwardly projecting teeth adapted to engage the inner face of the fibrous strip to prevent the same from slipping downwardly on the 30 leg.

In testimony that we claim the foregoing as our invention we have signed our names in presence of the subscribing witnesses this 4th day of May, 1918.

HARRY T. LOOMIS.
DOROTHY Z. HUNT.
